CIGARETTE LIGHTER

Arthur Dubsky, New York, N. Y., assignor to Austam Manufacturing Corp., a corporation of
New York

Application November 14, 1950, Serial No. 12,983

Term of patent 14 years

(Cl. D48—27)

To all whom it may concern:

Be it known that I, Arthur Dubsky, a citizen of the United States, residing in the city of New York, Borough and county of Queens, and State of New York, have invented a new, original, and ornamental Design for a Cigarette Lighter, of which the following is a specification, reference is being made to the accompanying drawings, constituting a part hereof, wherein,

Fig. 1 is a top plan view of a cigarette lighter, showing my new design;

Fig. 2 is a side elevational view thereof;

Fig. 3 is a front elevational view of the same;

Fig. 4 is a side elevational view, similar to Fig. 2, but showing the lighter in operation; and

Fig. 5 is a front elevational view, similar to Fig. 3, but showing the lighter in operation as illustrated in Fig. 4.

I claim:

The ornamental design for a cigarette lighter, substantially as shown.

ARTHUR DUBSKY.
